UNITED STATES PATENT OFFICE.

WILLIAM C. DUFFEY, OF CALHOUN, GEORGIA.

GUIDE FOR SEWING HARNESS.

SPECIFICATION forming part of Letters Patent No. 256,988, dated April 25, 1882.

Application filed September 19, 1881. (Model.)

To all whom it may concern:

Be it known that I, WILLIAM C. DUFFEY, of Calhoun, in the county of Gordon and State of Georgia, have invented certain new and useful 5 Improvements in Sewing-Guides for Harness-Work, of which the following is a specification.

The invention consists in a sewing-machine attachment formed of a spring-plate attachable to the bed of a machine so as to hold the guides 10 and channeling-knives above said bed and allow of their adjustment by slots and screws, as hereinafter described.

Reference is to be had to the accompanying drawings, forming part of this specification, in which similar letters of reference indicate corresponding parts in all the figures.

In the drawings, Figure 1 is a side elevation of the guide at the feeding side. Fig. 2 is a plan view of the same. Fig. 3 is a sectional 20 side view in reverse of Fig. 1; and Fig. 4 is a detail view, showing the relative position of the guide-rollers and the cutters.

The guide is to be used with any manufacturing sewing-machine.

25 A represents the bed-plate of such a machine.

B is the body of the attachment, consisting of a metal plate bent at the end, by which it is attached to the bed, the attachment being 30 by screws a.

b b are slides carrying guide-rollers c c, and held in slots d of plate B by clamping-screws e, so that the rollers can be set at the proper distance apart. Between the slots d the plate 35 B is arched, and a screw, f, in the arched portion carries at its lower end a pressure-roller, g. By this construction the plate B serves as a spring-arm that presses roller g upon the material with more or less force, according to adjustment of screw f.

The channeling or grooving knives h h are attached to plate B by a screw, i, tapped through the knife-plates, so that the knives extend behind the guide-rollers, one above and the other

below the plate. The upper knife is provided 45 with an adjusting-screw, k, bearing on plate B, so that the cutting-edge is retained at the proper elevation. The upper knife, h, also carries a screw, l, that extends through a slot in plate B and bears on the lower knife for use 50 in pressing the knife ends apart.

The attachment is to be adjusted on the machine-bed to bring the cutting-edges of the knives in line with the needle. The material passes beneath roller g and between rollers c 55 c, and the knives, acting upon the upper and under side, cut a groove or channel for the stitching. By adjusting the slides b carrying rollers c, the groove is formed at the desired distance from the edge.

60 Either knife can be used without the other, and the cutting-edges be shaped to form a groove of suitable size, according to the character of work.

The guide can be used for making round 65 reins and stitching traces and straps. It is also adapted for use for raised stitching, which can be done without the pressure-roller bearing on the raised portions.

I am aware that it is not broadly new to 70 combine two horizontal guide-rolls with an upper and lower channeling-knife; but

What I claim as new is—

A slotted and apertured plate-spring, B, arched to carry the top guide, twice bent at one 75 end where it is to be attached to the bed A, carrying the channeling-knives on opposite sides, the pressure-roll suspended from the arch, and the side rolls arranged on each side of the arch, said knives and the holders of the 80 rolls being adjustable by screws, whereby there is formed an attachment which may be used in connection with a sewing-machine, as and for the purpose specified.

WILLIAM C. DUFFEY.
